OF D 12,028

Design No. 12,028, dated November 9, 1880.

UNITED STATES PATENT OFFICE.

CHARLES MAGEE, OF BROOKLYN, NEW YORK, ASSIGNOR TO THE BIGELOW CARPET COMPANY, OF CLINTON, MASSACHUSETTS.

DESIGN FOR CARPET.

SPECIFICATION forming part of Design No. 12,028, dated November 9, 1880.

Application filed September 1, 1880. Term of patent 3½ years.

To all whom it may concern:

Be it known that I, CHARLES MAGEE, of Brooklyn, in the county of Kings and State of New York, have invented a new and original Design for Carpet, of which the following is a specification.

This invention relates to a new and original design for carpets and similar fabrics; and it consists in the novel grouping and configuration of figures hereinafter more fully described.

The accompanying photograph illustrates a face view of a carpet having my new design.

D is a stripe which runs between two parallel ornamental bands, one formed of semi-rosettes set at intervals with link-like connecting-figures, and the other, h, containing a rectangular crenelated pattern with pendent figures hanging or projecting therefrom.

The stripe D is ornamented with the figure group F, containing a bunch of flowers, g, and leaves. The flowers g partly overlap a rectangular figure, f, ornamented with a spray of flowers, and having flowers projecting from one of its corners, which flowers connect it

with the next group, F. Parallel to this stripe D is a band, E, bordered on one side by the band h, before described, and ornamented with pointed flower-like figures. Parallel to this band E is another band or stripe, 30 G, ornamented with window-like arches k and separate flowers l, placed above the pillars of the arches.

I claim—

1. The design for carpets, consisting of the 35 group F, containing flowers g and field f, substantially as shown.

2. The design for carpets, consisting of the group F and the band h, substantially as shown.

3. The design for carpets, consisting of the bands G, E, and h, substantially as shown.

4. The design for carpets, consisting of the stripe D, containing the figures g and f and bands h, E, and G, substantially as shown.

CHARLES MAGEE.
